UNITED STATES PATENT OFFICE.

HANS CHRISTIAN TYSSE, OF MANISTEE, MICHIGAN, ASSIGNOR OF ONE-HALF TO
ALFRED C. CHRISTENSON, OF MANISTEE, MICHIGAN.

CUSHION-INNERSOLE.

1,132,132.

Specification of Letters Patent. Patented Mar. 16, 1915.

Application filed April 11, 1913. Serial No. 760,405.

To all whom it may concern:

Be it known that I, HANS CHRISTIAN TYSSE, a citizen of the United States, residing at Manistee, in the county of Manistee and State of Michigan, have invented certain new and useful Improvements in Cushion-Innersoles, of which the following is a specification.

This invention relates to boots and shoes generally, and more particularly to the inner sole therefor.

The primary object of the invention contemplates the provision of a metallic intermediate sole adapted to be arranged between the outer and inner soles of a boot or shoe to produce a chamber therebetween, which chamber materially adds to the comfort, care and proper conditioning of the foot of the wearer and prevents the penetration of dampness and cold into the shoe interior, thereby preventing rheumatism, gout, colds and various ailments commonly occurring by reason of the inefficient sole now forming a part of the ordinary shoe or boot.

A further object of the invention contemplates the provision of means including an intermediate metallic sole whereby the inner or foot engaging sole is yieldably supported, the said metallic sole being preferably composed of any suitable resilient or spring-like material.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is a side elevation of a shoe, partly broken away illustrating the application of the invention; Fig. 2 is a longitudinal sectional view of a shoe, the inner sole being partly broken away; and Fig. 3 is a plan view of the intermediate sole.

Referring now to the drawings, wherein are illustrated the preferred forms of my invention the numeral 1 designates a shoe of the ordinary type having the usual outer leather sole 2 and heel 3 forming a part

thereof. Arranged upon the top of the sole 2 and conforming with the outline of the upper face thereof, I provide an intermediate metallic sole or strip 4 the same being preferably composed of any suitable resilient or spring wire curled or waved for the purpose of creating a resilient or spring-like tread over which the inner sole 5 is disposed, the said inner sole being composed of any suitable material such as leather, felt or the like. In the preferred form the wires of the intermediate sole 4 extend diagonally of the shoe sole and in transverse relation with respect to one another and an outer wire strand is provided to which the transversely extending strands are secured, the said outer strand encircling the entire intermediate sole. The sole however may be composed of a single strand of wire curved or curled as above set forth and bent or twisted to create a resilient tread adapted to conform to the curvature or outline of the shoe within which it is arranged. By the provision of the intermediate sole between the inner sole 5 and the outer sole 2 a chamber is formed, which chamber will prevent dampness, cold or heat from entering the shoe interior and thereby materially decrease the cases of rheumatism, gout, colds or other ailments resulting from various causes brought about by the unsatisfactory manner in which shoe soles are at present constructed.

While I have shown the intermediate and inner soles as forming a part of the shoe, the same being connected thereto through the medium of nails 6, such connection may however be eliminated and the inner and intermediate soles detachably arranged upon the interior of the shoe so as to permit removal thereof should occasion demand. The provision of the intermediate sole also creates a cushion or resilient support for the inner sole thus adding materially to the comfort of the shoe when worn.

It will be seen from the above, taken in connection with the accompanying drawings that an air chamber is formed between the inner and outer soles of the shoe, which chamber prevents the penetration of dampness, etc., into the interior of the shoe; that by twisting and curling the wire strand sufficient thickness is produced by the intermediate sole to create the desired space between the said inner and outer soles; and that by the provision of a detachable tread or inner

sole, the same may be quickly removed and applied to any shoe as at present constructed.

In reduction to practice, I have found 5 that the form of my invention, illustrated in the drawings and referred to in the above description, as the preferred embodiment, is the most efficient and practical; yet realizing that the conditions concurrent with the 10 adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

20 1. In a shoe, the combination of an outer sole, an intermediate sole arranged thereupon, the said intermediate sole comprising a plurality of independent resilient wire strands extending transversely of the sole, 25 each strand being coiled to form a yieldable

springy support, and an inner sole supported by the said intermediate sole in spaced relation to the said outer sole, as and for the purpose set forth.

2. In a shoe, the combination of an outer 30 sole, an intermediate sole arranged thereupon, the said intermediate sole comprising a plurality of independent resilient wire strands extending transversely of the sole, each strand being coiled to form a yieldable 35 springy support, a securing strand, the said securing strand being coiled throughout its entire length and engaging the ends of said transverse strands to secure the latter against displacement, and an inner sole supported by the said intermediate sole in 40 spaced relation to the said outer sole, as and for the purpose set forth.

In testimony whereof I affix my signature in presence of two witnesses.

HANS CHRISTIAN TYSSE.
